UNITED STATES PATENT OFFICE

2,465,434

LABORATORY DEVICE

Lucien W. Druge, Riverside, Ill., assignor to Universal Oil Products Company, Chicago, Ill., a corporation of Delaware

Application May 20, 1947, Serial No. 749,227

1 Claim. (Cl. 210—160)

1

This invention relates to an improved laboratory device for converting an ordinary funnel into a vacuum funnel for rapid filtering. More specifically the novel device provides a conical insert member suitable for holding a filter paper within a funnel in a manner which permits vacuum filtering, and in addition thereto, the device provides for the easy removal of the filter paper and its retained material from the funnel.

The usual type of vacuum funnel, such as the Buchner funnel, has a non-removable perforated bottom and the filter paper, which is placed within the funnel, must ordinarily be dug out of the funnel after use, rather than easily lifted out. The vacuum funnel also has a relatively flat perforated bottom section such that the filter paper, cloth, or other filtering membrane, must rest in a substantially flat manner within the funnel and a certain amount of the filter-cake, or retained particles, are deposited on the walls of the funnel and therefore are not entirely recovered within the limits of the paper.

The principal object of this invention is to provide a device which may be inserted in an ordinary sloping wall type of funnel and provide means for converting the latter into a vacuum funnel.

It is also an object of the invention to provide a removable insert for a funnel which is adapted to hold a filter paper in a well supported manner and which will permit easy removal of the paper with its retained filtered particles.

Briefly, the device of my invention comprises, a perforated cone-shaped member which is adapted to be inserted within an ordinary sloping wall funnel, a gasket member attached to and encircling the outer periphery of the insert member at the enlarged end thereof, with the gasket member being arranged to project slightly from the outer surface of the cone-shaped insert and providing thereby a sealing and supporting ring for the device when it is placed within a funnel. The perforated cone-shaped member thus provides means for holding a filter paper in a well supported manner at a spaced distance from the inner sloping wall of the funnel, and such that there is the necessary space for applying vacuum to the entire insert to effect rapid filtering. The upper and outer surface of the perforated member is preferably provided with a groove or recess such that the gasket may be maintained in a relatively fixed position and be tightly sealed to the insert member. Also, the gasket member is preferably of a soft rubber-like or resilient material such that a good air seal may be obtained at the

2

upper end of the space provided between the perforated insert member and the funnel wall.

The design and construction of this novel insert is such that it not only provides a vacuum type of funnel, but simultaneously gives the user many desirable advantages. A filter paper may be easily placed within the insert, and when it is being used there is no danger of the lower tip end of the filter paper being ruptured and the contents spilled. Also, there is no difficulty in removing the paper and the retained material from the funnel as the entire insert and paper may be removed together. In many laboratories, it is a practice to place a backing strip of gauze around the lower end of a filter paper in order to prevent rupturing of the tip end, however, use of the insert member will obviate the necessity of taking this prevention and will make all filtering operations in general much easier to perform. The cone-shaped insert may be constructed of many types of materials such as glass, a ceramic material, metal or metal alloy, while the gasket member may be made of rubber or other soft rubber-like material.

Another advantageous feature of the novel device, is that it may be made in a very inexpensive manner to fit most standard sized funnels and may be used therein to carry out ordinary filtering operations, in addition to vacuum filtering. Since the device may be used to carry out vacuum filtering, one or more of them may be maintained in the laboratory to supplant the more expensive type of vacuum funnels.

The accompanying drawing will serve to illustrate the construction of one embodiment of the device, as well as to indicate how it may be inserted in an ordinary type of funnel.

Referring now to the drawing, there is shown a perforated cone shaped member 1, which is adapted to be placed within any ordinary type of sloping wall funnel 2, the latter being indicated by the dotted lines. A gasket member 3 is placed around the upper and exterior side wall of the insert member 1. This gasket 3 is preferably placed near the upper end of the device at a point above the multiplicity of perforations 4, which are provided through the wall of the insert member 1. The gasket is also attached to the cone shaped member 1 in a manner to project slightly from the outer surface thereof and to thereby provide a small annular space between the surface of the insert member and the inner wall of the funnel when the device is placed and supported within an ordinary type of funnel. In a preferable embodiment of the device, a slight

groove or recess is provided within the wall of the cone-shaped member 1 in order to accommodate the gasket 3 such that it will be retained in a fixed position and will not slip from the outer wall of the device.

In operating and using the device to convert an ordinary type of funnel into a vacuum funnel, the insert is placed within a funnel and the combination is used in substantially the same manner that a Buchner funnel is employed. The funnel 2 may be inserted into a receiving bottle, with a rubber stopper or other sealing means, and vacuum applied to the receiving bottle such that filtrate is rapidly drawn through the device and collected therein while the filtered particles or filter-cake is retained on the filter paper, or other like membrane, which has been inserted within the perforated cone-shaped insert 1. The vacuum action from the receiving bottle is exerted uniformly around the insert 1 since the gasket 3 serves to support the member in a spaced manner from the wall of the funnel 2. After the filtrate has been drawn through the device and the filtered material is retained therein, the entire insert 1 with the filter paper and material may be removed from the funnel 2, and the recovered material subjected to further desired treatment or analysis, without there being any loss of the material.

As previously noted hereinabove, the drawing shows one preferable embodiment, however, the invention is not to be limited strictly to the construction and arrangement which is shown. The size and spacing of the perforations within the cone-shaped member may be varied to provide varying percentages of open area to total area, or the perforations may be of varying shapes, such as slots, squares, or the like. The gasket member 3 may have other than a rectangular cross-section and may also be attached to the cone member 1 in a somewhat different manner from

that illustrated, so long as it is made to project slightly from the outer surface of the perforated insert and provides the necessary air space around the insert when placed within a funnel.

5 I claim as my invention:

A device for holding a filter paper and for converting a funnel to one of the vacuum type, comprising in combination, a perforated cone-shaped member constructed of a single piece of rigid material and adaptable for insertion within a sloping wall funnel, a gasket retaining recess on the exterior surface of said one-piece member at the upper enlarged portion thereof and a gasket member positioned within said recess, said 10 gasket being tightly attached and sealed to said member within said recess and of a size sufficient to project a short distance from the outer surface of said conical perforated member, said gasket providing thereby means for sealing and supporting said insert within said funnel at a spaced 15 distance from the inner wall of the latter.
